UNITED STATES PATENT OFFICE.

WILLIAM A. LORENZ, OF HARTFORD, CONNECTICUT, ASSIGNOR TO UNION PAPER BAG MACHINE COMPANY, OF PHILADELPHIA, PENNSYLVANIA, A CORPORATION OF PENNSYLVANIA.

PAPER-BAG MACHINE.

No. 877,205.

Specification of Letters Patent.

Patented Jan. 21, 1908.

Application filed January 26, 1905, Serial No. 242,766.

To all whom it may concern:

Be it known that I, WILLIAM A. LORENZ, a citizen of the United States, and resident of Hartford, in the county of Hartford and 5 State of Connecticut, have invented certain new and useful Improvements in Paper-Bag Machines, of which the following is a full, clear, and exact specification.

This invention relates to paper bag machines of the class which form square bottom bags from bellows-sided tubes or blanks; and it has to do particularly with what is well known as the diamond forming operation.

The invention herein shown is a modification of the invention described in my Patent 15 No. 847,191 dated March 12, 1907. The machine therein described employs an oscillatory folding plate provided with a defining edge over which one of the plies of the blank 20 is folded to form the diamond while the blank is held on a suitable carrier. The folding plate is mounted so that it is near to the adjacent surface of the carrier at the initial movement of the oscillation, the axis of os- 25 cillation being also in close proximity to the surface of the carrier, though at some distance from the defining edge. In order to permit the defining edge to clear the adjacent surface of the carrier during the oscillations 30 of the folding plate, this adjacent portion of the surface of the carrier is not integral with the rest of the surface, but is pivoted thereto at its forward end and is provided with means for swinging it on this pivot away 35 from the folding plate, thus securing the necessary clearance, the surface of the swinging portion being flattened for a distance back from the diamond holder in order to relieve the paper of the undue strain to which it 40 would be subjected if made to conform during the diamond forming operation to the generally cylindrical surface of the carrier.

In the machine of the present invention the swinging portion of the carrier surface is 45 pivoted at its rear end instead of its front end to the carrier. The effect of this is to withdraw support from beneath the lower 50 ply of the blank between the diamond holder and the tuck holders during the early part of the diamond forming operation and thus allow the paper to assume the shape into which this operation naturally carries it.

Figure 1 is a sectional side view of as much 55 of the mechanism as is necessary to show the present invention, the section being taken

through the machine at one side of the carrier. Fig. 2 is a fragmentary side view on a slightly enlarged scale, and shows the swinging surface in its inner position. Fig. 3 is a partial front view of Fig. 2. Fig. 4 is a view 60 similar to Fig. 2 but with the swinging surface in its outward position. Fig. 5 is a partial front view of Fig. 4.

The general construction of the machine herein shown is similar to that described in 65 my patent above referred to, to which reference may be made for such details as are not fully shown and described herein.

The feed rolls 13 and 14 (Fig. 1) which receive the blanks B from any suitable tube 70 forming and cutting-off mechanism are secured to the shafts 15 and 16 journaled in the uprights 12. Disposed adjacent to the meeting line of the two rolls 13 and 14, and in such position that the blank as it moves forward will pass beneath it, is the guide plate 57 supported on a bracket 37 which is pivoted on a stud 58 appurtenant to the upright 12. It is the function of the guide plate 57 to hold the front end of the blank down as it 80 passes forward from the rolls and prevents its colliding with the folding plate 40 in the return movement of the latter. The bracket 37 has an arm 59 which is provided with a cam roll 60 which is held by a spring 62 85 against the cam 61, the latter being secured to the lower roll shaft 15.

The oscillating defining plate 40 is disposed adjacent to the carrier 23 in such a position that the blank B will pass beneath 90 it from the underside of the guide plate 57. The defining plate 40 is provided with box holders 42 and is secured at its inner end to the trunnioned bracket 41 while the outer end is arranged to slide endwise on another 95 trunnioned bracket 56. The oscillating movement of the defining plate 40 and its advancing movement as well as the operation of the box holders 42 is or may be effected by means of mechanism like that 100 shown and described in my aforesaid patent, which also shows and describes the construction and operation of the drop plate 72 together with the driving rolls 77, deflecting plate 79 and delivery rolls 80 and 81.

The rotating carrier 23 which holds and sustains the blank B during the diamond forming operation is secured to the shaft 24 journaled in bearings in the side frames 12. The carrier 23 is provided with two sets of 110

blank holding devices which hold the lower 50 ply of the blank in position while the upper 55 ply is being turned back, and which operate alternately on the blanks. Each set includes a diamond holder 32 which is pivoted on a stud 33 (Fig. 2) appurtenant to the carrier 23 and has an arm 33' provided with a roll 34 held in engagement with a fixed cam 35, by means of a spring 36, so that it grips 10 and releases the front end of the blank at proper intervals. The cam 35 is secured to one of the bearings of the shaft 24.

As thus far described the machine of the 15 patent referred to and that of the present application are substantially the same. The novel arrangement of the swinging support 86 which, with the tuck-holders 27 makes up the remainder of the set of blank-holding 20 devices, will now be described.

Each swinging blank support 86 is pivoted 25 at its rear end at 87 to the carrier 23 and has a roll 88 mounted on an extension 91 on its under side, which roll is held in engagement with a fixed cam 89 by means of a spring 90 (Fig. 4) thus causing the support 86 to swing 30 towards and from the center of the carrier 23 as the latter rotates. The tuck holders 27 are disposed on opposite sides of the swinging support 86 in position to grip the lower 35 edges of the tuck to the support and are operated by means substantially like those shown in the above mentioned patent.

In this machine, as in the machine of the 40 aforesaid patent, the movement of the swinging support towards the center of the carrier 23 enables the defining edge 39 to pass clear of the support during the oscillation of the plate 40, as shown in Fig. 2. But in this machine the support 86 being thus pivoted 45 at its rear end, its movement toward the center of the carrier withdraws from those portions of the blank between the diamond holder and the tuck holders, and leaves the blank unsupported between these places. It also carries the tuck holders downward 50 and with them the adjacent portions of the blank, so that the paper is relieved of the strain to which its front end would be subjected were it held closely to the surface of the support 86 during the folding back of the 55 upper ply. The tendency of the paper to tear or wrinkle or to otherwise fold imperfectly during this operation is thus largely overcome. At the same time the front end 60 of the blank is still held by the diamond holder 32 in its original position on the surface of the carrier 23.

It is not essential that the diamond holder 65 32 should grip the paper. It is sufficient for it to merely stand close to and above the front end of the lower ply and hold it from rising during the diamond forming operation. The rear part of the support 86 need not be concentric with the surface of the carrier 23, 70 as it may be flattened or otherwise cut away

at that place. Nor is it essential that the coöperating devices for folding the diamond on the blank support shall be precisely as shown. Other coöperating devices may be employed without departing from the spirit 75 of this invention.

The consecutive operation of the machine is as follows:—The blank B properly formed and cut to length is fed between the rolls 13 and 14 which carry it forward beneath the 75 guide plate 57, and the defining plate 40, in which position the forward end is gripped to the carrier 23 by the diamond holder 32. The box holders 42 and the tuck holders 27 now enter the tucks on both sides and grip the 80 upper and lower plies of the blank to the defining plate 40 and the swinging support 86. As the blank moves forward with the carrier 23, the folding plate 40 swings on its axis and folds back the upper ply, while the support 85 86 swings downward to permit the defining edge 39 to pass clear of it. This latter movement carries the tuck holders 27 downward while the end of the diamond holder 32 still retains the end of the blank in its original position on the carrier 23, as shown in Figs. 2 and 3. As the carrier 23 continues its forward movement, the defining plate 40 folds the upper ply still further over, and the swinging support 86 returns to its original position, 90 thus bringing the parts to the position shown in Figs. 4 and 5, the folds of the blank being flattened down to place by the drop plate 72 which has in the mean time swung forward. The diamond holder 32 now releases its hold 100 and the blank is carried from the carrier 23 by the driving rolls 77 and the deflecting plates 79 to the delivery rolls 80 and 81 from whence it passes on to any suitable pasting and flap folding mechanism.

Some of the features herein shown are 105 shown, described and claimed in my aforesaid patent 847,191. In so far as this application shows features which are also shown and described in the said patent it is to be 110 regarded as being subordinate to said patent.

In my prior patents numbers 840,073, 847,191, 847,193 and 847,195 I have shown, described and claimed more or less broadly various mechanisms for holding and folding a 115 paper bag blank in ways in which the front end of the lower ply is supported in a raised position relative to the plane in which the triangular folds are formed, the object being, as in the present case, to relieve the front end 120 of the paper from strain during the formation of those folds. In so far as it may be considered that the present application shows features of construction, or arrangement in common with the said prior patents, it is to 125 be regarded as being subordinate to these patents.

I claim as my invention:—

1. In a paper bag machine, means for forming diamond folds on bellows sided 130

- blanks, having in combination a rotating blank carrier, a diamond holder for holding the front end of the blank relative to the carrier, a blank support mounted upon the carrier to move toward and away from the diamond holder, and having means for holding the lower ply of the blank, means for turning back the upper ply of the blank to form the diamond fold, and means for moving the blank support relative to the diamond holder, during the diamond forming operation. 5
2. In a paper bag machine, mechanism for forming diamond folds on bellows sided blanks, having in combination a rotating blank carrier, a diamond holder mounted on the blank carrier for holding the front end of the blank relative to the carrier, a blank support pivotally mounted upon the carrier for oscillation toward and away from the diamond holder, and having tuck holders for engaging the lower tucks of the blank, means for turning back the upper ply to form the diamond fold, and means for oscillating the blank support relative to the diamond holder 10 during the diamond forming operation. 15
3. In a paper bag machine, mechanism for forming diamond folds on bellows sided blanks, having in combination a rotating blank carrier, a diamond holder for holding the front end of the diamond relative to the carrier, a blank support pivoted to the carrier on an axle remote from the diamond holder, tuck holders mounted upon the blank support between the said axis and the diamond holder, means for turning back the upper ply of the blank to form the diamond folds, and means for oscillating the blank support relative to the diamond holder 20 during the diamond forming operation. 25
4. In a paper bag machine, mechanism for forming diamond folds on bellows sided blanks, having in combination a rotating blank carrier, a diamond holder for holding the front end of the diamond relative to the carrier, a blank support pivoted at its rearward end to the blank carrier, with its free swinging end extending forwardly toward the diamond holder, tuck holders mounted on the blank support between the axis thereof and the diamond holder, means for turning back 30 the upper ply of the blank to form the diamond fold, and means for oscillating the blank support relative to the diamond holder during the diamond forming operation. 35
5. In a paper bag machine, mechanism for forming diamond folds on bellows sided blanks, having in combination a rotating blank carrier, a diamond holder for holding the front end of the diamond relative to the carrier, a blank support pivoted at its rearward end to the carrier, with its forward end extending toward the diamond holder, a defining plate mounted for oscillation in a curved path above the rotary path of the bed, provided with means for turning back the upper ply of the blank to form the diamond fold, and means for swinging the forwardly extending free end of the blank support away from and toward the diamond holder 40 during the diamond forming operation. 45
6. In a paper bag machine, mechanism for forming diamond folds on bellows sided blanks, having in combination a rotary blank carrier, a diamond holder for holding the front end of the diamond relative to the carrier, a blank support having its rearward end pivotally mounted upon the blank carrier upon an axis remote from the diamond holder, with its free end extending forwardly 50 toward the diamond holder, a defining plate mounted for oscillation in a curved path above the rotary path of the bed, and provided with means for engaging and turning back the upper ply of the blank to form the diamond fold, means for oscillating the defining plate, and means for swinging the forwardly extending end of the blank support away from and toward the diamond holder, 55 during the diamond forming operation. 60

In testimony whereof I have signed my name to this specification in the presence of two subscribing witnesses.

WILLIAM A. LORENZ.

WM. H. HONISS.

It is hereby certified that in Letters Patent No. 877,205, granted January 21, 1908, upon the application of William A. Lorenz, of Hartford, Connecticut, for an improvement in "Paper-Bag Machines," an error appears in the printed specification requiring correction, as follows: In line 32, page 3, the word "axle" should read *axis*; and that the said Letters Patent should be read with this correction therein that the same may conform to the record of the case in the Patent Office.

Signed and sealed this 11th day of February, A. D., 1908.

[SEAL.]

C. C. BILLINGS,
Acting Commissioner of Patents.
